United States Patent Office

Des. 220,550
Patented Apr. 20, 1971

220,550

PIANO

Winsor D. White, Jr., Blowing Rock, N.C., assignor to
D. H. Baldwin Company, Cincinnati, Ohio

Filed Feb. 24, 1970, Ser. No. 21,585

Term of patent 14 years

Int. Cl. D17—01

U.S. Cl. D56—9

FIG. 1

FIG. 2FIG. 3

FIG. 1 is an angular perspective view of a piano embodying my new design.

FIG. 2 is a front elevational view thereof.

FIG. 3 is a side elevational view thereof.

The back of the piano (not shown) is conventional. The side (not shown) is the same as the side shown.

I claim:

The ornamental design for a piano, substantially as shown and described.
